UNITED STATES PATENT OFFICE

LOUIS BECHEREAU, OF PARIS, FRANCE, ASSIGNOR TO SOCIETE DES AVIONS BERNARD,
OF PARIS, FRANCE

AEROPLANE

Application filed February 4, 1929, Serial No. 337,342, and in Belgium February 9, 1928.

The present invention relates to aeroplane construction and assembly.

One of the objects of the invention is to provide a method and means for assembling 5 aeroplanes which will permit various types of machines to be produced from standardized units.

Another object is to provide a special form of wing structure combining both 10 lightness and strength.

Further objects will appear in the course of the detailed description now to be given with reference to the accompanying drawings, in which:—

15 Figs. 1 and 2 are sections taken on line 1—1 of Fig. 2 and, on line 2—2 of Fig. 1, respectively;

Fig. 3 represents a side view of an assembled machine;

20 Fig. 4 to 6 show partial assemblies of the machine illustrated in Figs. 1 to 3;

Fig. 7 is a perspective showing one form of wing structure;

Fig. 8 shows the internal extremity of the 25 same wing;

Fig. 9 represents, in section, a second form of wing structure;

Fig. 10 is a plan of a wing of the type shown in Fig. 9;

30 Fig. 11 is a front view of a wing during the process of manufacture.

Referring to the various figures of the drawings, there is shown a motor unit *a*,—a wing-fuselage unit *b*, *b*¹,—an alighting unit *c*,—and a tail-body unit *d*. These various units are tied together by bolts or pins *e* or by equivalent structures.

Assemblies of this type have the advantage of permitting the replacement of any 40 unit by another of different design whereby any desired type of aeroplane may be obtained. It will be noted further that, since the wings are integral with part of the fuselage, the latter supports the former throughout its height. The mean plane passing through the base of the wings should lie between those of the fuselage longerons and may pass through the axis of traction as shown in Fig. 1, such an arrangement making the machine easy to manoeuvre, and im-

proving its aerodynamic qualities. Obviously the wings may be mounted either above or below the fuselage level and may be made either integral with, or detachable from, that part of the fuselage serving to accommodate the pilot's legs. However, there are special advantages in making wing-fuselage assembly *b*, *b*¹ in an integral block, this form of construction being unusually rigid and permitting rapid change of the wings in case of breakage. Whether the integral or detachable form of assembly be used, the wings should join centrally so as to embrace or form compartment *b*¹ for the pilot's legs.

55 In the wing structures shown in Figs. 7 to 10, a series of vertical portions *A* are fitted at each end with closures *B* and maintained at fixed distances by transverse elements *C*, elements *A*, *B* and *C* cooperating 60 to form three layers of superposed cells. Contiguous partitions *C* may lie in the same plane (Fig. 7) or in parallel planes (Fig. 9). Partitions *A* should extend continuously from one surface of the wing to the 65 other and be of considerably less thickness than closures *B*. It is not necessary that partitions *A* form solid walls. Since, as will be shown further on, these walls are formed of strips, spaces may be left between 70 adjacent strips, so as to lighten the wing structure.

75 To complete wing may if desired, be assembled from finished elements. However, the wing design is such as to permit a rough assembly of all-rectangular elements which may then be finished to the shape desired. Elements *B* forming the air-resisting surfaces may be cut out of wood or the like in rectangular form (Fig. 7), supported between walls *A*, the latter being laid down obliquely (Figs. 7 and 11) in the form of rectangular strips (Fig. 11), and the whole assembly may then be cut down to finished contour. Preferably, the strips forming 80 partitions *A* should, for adjacent partitions, be oblique in opposite directions (and, as noted above, may or may not be in contact with one another). This form of construction permits a wing to be assembled quickly 85 90 95 100

and cheaply and yields an unusually stout and light structure. The assembly is completed by the usual covering material D.

It is sometimes advantageous to leave a notched portion near the free extremity of the wing (Fig. 10) so as to lighten the wing structure. The cellular form of construction permits this to be done without sacrifice of strength in contiguous portions of

10 the wing.

What I claim is:—

1. A wing structure composed of a series of partitions extending continuously from one wing surface to the other, said partitions being positioned in the direction of the length of the wing, and spacing elements adapted to maintain said partitions at a fixed distance from one another, said spacing elements lying in spaced relation to the wing

20 surfaces.

2. A wing structure comprising a group of longitudinal elements positioned to form one air-resisting surface, a group of longitudinal elements positioned so as to form 25 a second air-resisting surface, and substantially parallel strips extending from one group of longitudinal elements to the other, said strips lying obliquely with relation to said longitudinal elements.

3. A wing structure including a plurality of longitudinal elements adapted to form one air-resisting surface, a plurality of longitudinal elements adapted to form a second air-resisting surface, a first series of 35 substantially parallel strips extending obliquely from one air-resisting surface to the other, and a second series of strips extending obliquely from one air-resisting surface to the other in a different direction than said

40 first series of strips.

4. A wing-fuselage unit adapted to coact with motor, and body units to form an airplane, said wing-fuselage unit comprising a pair of wings bifurcating centrally so as 45 to enclose a space adapted to form part of a fuselage.

5. A structure as defined in claim 2 in combination with a plurality of longitudinal bracing elements extending between adjacent parallel strips, said bracing elements being positioned in spaced relation to the wing surfaces.

6. A wing structure comprising a plurality of longitudinal elements positioned to 55 form one air-resisting surface, a plurality of longitudinal elements positioned to form a second air-resisting surface, strips inserted between adjacent longitudinal elements 60 forming the first of said air-resisting surfaces, each of said strips extending to, and being inserted between, adjacent longitudinal elements forming said second air-resisting surface, and a spacing element extending 65 between a pair of strips, said spacing

element being positioned in spaced relation to each of said air-resisting surfaces.

In testimony whereof I have signed this specification.

LOUIS BÉCHEREAU.
